UNITED STATES PATENT OFFICE.

LEON COHEN, OF ST. LOUIS, MISSOURI.

ADJUSTABLE HAT CONFORMER AND RETAINER.

1,144,462.

Specification of Letters Patent. Patented June 29, 1915.

Application filed July 30, 1914. Serial No. 854,047.

To all whom it may concern:

Be it known that I, LEON COHEN, a citizen of the United States, and resident of St. Louis, Missouri, have invented certain new and useful Improvements in Adjustable Hat Conformers and Retainers, of which the following is a specification containing a full, clear, and exact description, reference being had to the accompanying drawings, forming a part hereof.

My invention relates to improvements in adjustable hat conformers and retainers, and the object of my invention is to construct a simple and inexpensive device arranged to be secured within a hat crown, for the purpose of conforming the hat to different sized heads or to adapt the hat to different coiffures, as well as to serve as a means for retaining the hat in place without the employment of extraneous securing devices, such as the ordinary hat pins, which, as is well known, deteriorate the hats, and to construct the device in such manner that it may be either expanded or contracted after being secured in the hat.

With the above purposes in view, my invention consists in certain novel features of construction and arrangement of parts which will hereinafter be fully described, pointed out in my claims, and illustrated by the accompanying drawings, in which:

Figure 1 shows a simple, sectional elevation of a hat having the device of my invention secured therein; Fig. 2 is a fragmental inverted plan of a hat with my improved device therein; Fig. 3 is an enlarged fragmental sectional elevation showing the detailed construction of the device; and Fig. 4 is a perspective showing the terminal ends of the device removed from the hat.

Referring by numerals to the accompanying drawings: 5 designates the crown and 6 the brim of the hat, which are of ordinary construction and of themselves form no part of my invention. The crown and brim may vary infinitely as to configuration and relative dimensions, as fashion dictates, without altering the design or utility of my improved device.

The body portion of my improved device comprises two elongated, connected casings or tubes 7 and 8, preferably constructed of a single piece of flexible textile material, which casings are made parallel, but when in use are substantially at right angles, rela-

tively. Secured in one of these casings or tubes (8) is a strip 9 of relatively stiff material, such as buckram, preferably reinforced by the wires 10, which strip 9 and the wires 10 extend beyond the casing 8 at one end to produce a tongue 11 arranged to be inserted in the opposite open end of the casing for purposes hereinafter made clear. In order to hold the strip 9 in place against longitudinal movements within the casing 8, I secure the strip by a line of stitches 12. The casing 7 is open at both ends and is adapted to receive an elastic cord 13 having greater length than the casing, so that its ends will project beyond the casing and be accessible to tying and untying, as required for the adjustment of the cord. Secured at one end of the casing 7 is a tongue 14 of relatively stiff material, such as buckram, which is arranged to be inserted in the opposite open end of the casing 7.

In applying the device to a hat, I secure the reinforced casing or tubular portion to the hat by a line of stitches 15, which are disposed next adjacent the casing 7 and extend around the entire device and hat crown, care being taken, of course, not to close the open end of the casing 8 opposite the tongue 11, and it being understood that the tongue 11 was inserted in the open end of the casing 8 prior to its securing by stitches to the hat crown. The tongue 14 is then inserted in the open end of the casing 7, and the elastic cord is then drawn and secured to the tension desired, which act moves the casing 7 to occupy a position approximately at right angles to the casing 8; or to a position which will engage the wearer's head or hair in a plane substantially at right angles thereto.

It is obvious from this construction that the entire device may be either expanded or contracted as required, to fit different sized heads or different coiffures, and that the tension of the cord may be varied as desired without effect on the body of the device.

Such a device may be manufactured and sold independent of the hats, and by reason of its adjustability will fit various sizes of hats, be adjusted in the same hat to fit different coiffures, and provides an elastic cord adjustment to suit the requirements and comforts of the wearer.

Having thus described my invention, what I claim as new therein and desire to secure

by Letters Patent of the United States therefor, is:

1. A device of the class described, comprising a pair of parallel connected casings, a relatively inflexible reinforce for one of said casings, said reinforce at its one end arranged to be inserted into the opposite end of the casing with which it is associated and an elastic cord within the other casing, 10 said casings being substantially at right angles, relatively, when in use.
2. A device of the class described, comprising a pair of parallel casings constructed from a single piece of flexible material, a 15 relatively inflexible reinforce within the one

casing, one end of which projects beyond the casing for insertion in the opposite end of the casing to provide for adjustment and continuity, and an elastic, flexible cord carried by the other casing, said casings being 20 substantially at right angles, relatively, when in use.

In testimony whereof, I have signed my name to this specification, in presence of two subscribing witnesses.

LEON COHEN.
